UNITED STATES PATENT OFFICE.

MINOTT W. SEWALL, DECEASED, LATE OF NEW YORK, N. Y., BY SUSANN E. SEWALL,
EXECUTRIX, OF NEW YORK, N. Y., ASSIGNOR TO THE BABCOCK & WILCOX COMPANY,
OF BAYONNE, NEW JERSEY, A CORPORATION OF NEW JERSEY.

STEAM-BOILER.

1,161,985.

Specification of Letters Patent. Patented Nov. 30, 1915.

Application filed July 30, 1914. Serial No. 854,156.

To all whom it may concern:

Be it known that MINOTT W. SEWALL, late a citizen of the United States and a resident of the city, county, and State of New York, did invent certain new and useful Improvements in Steam-Boilers, of which the following is a specification.

This invention relates to steam boilers and more particularly to a system of tubing, part of which constitutes a water-protected roof for the furnace of a Stirling boiler.

The invention will be understood by reference to the accompanying drawing which is a vertical section partly in outline, of a Stirling boiler with the present improvement.

In the drawing the numerals 1, 2 and 3 indicate the usual upper transverse steam and water drums of a Stirling boiler, these drums being connected by banks of generating tubes with a lower mud drum 4, all as usual and well-known in this class of boilers.

5 indicates the furnace chamber at the rear of which is a bridge wall 6. Supported upon said wall in front of the mud drum 4 is a supplemental transverse drum 7, said drums being connected by pipes 8. Supported in the front wall above the furnace door, parallel with and intermediate the levels of the upper and lower drums, is a transverse drum or water chamber 9, and this is connected to the supplemental drum 7 by a row of tubes 10 curved at their lower ends and having a general upward inclination. The tubes 10 support a baffle 11 extending from chamber 9 toward the rear of the combustion chamber, said tubes and baffle constituting the roof of the furnace chamber. Baffle 11 terminates short of the plane of the bridge wall so as to permit the 35 gases to escape into the secondary combustion chamber above the roof and among the tubes of the first bank. Any approved system of baffling may be employed for the generating tubes. The drawing shows the 40 standard baffle 12 at the rear of the first bank of tubes 13.

A series of substantially vertical tubes 14 connect chamber 9 with the front steam and water drum 1, thereby permitting a free 45 circulation from drum 4 through the supplemental drum 7, roof tubes 10, manifold 9 and tubes 14 to the front upper drum.

What is claimed and desired to be secured by Letters Patent of the United States is:—

1. A water tube boiler having upper 55 transverse steam and water drums and a lower mud drum, banks of generating tubes connecting said drums, a supplemental drum located in front of said lower drum, tubes directly connecting said lower and supplemental drums, a transverse water chamber intermediate the levels of the upper and lower drums, tubes connecting said supplemental drum and chamber, and tubes connecting said chamber with the front upper 60 drum.

2. A water tube boiler having upper transverse steam and water drums and a lower mud drum, banks of generating tubes connecting said drums, a supplemental 70 drum located in front of said lower drum, tubes directly connecting said lower and supplemental drums, a transverse water chamber intermediate the levels of the upper and lower drums, tubes connecting said supplemental drum and chamber, a baffle extending from said chamber rearwardly, said tubes and baffle constituting a roof for the boiler furnace, and tubes connecting said chamber with the front upper drum. 75

3. A water tube boiler having upper transverse steam and water drums and a lower mud drum, banks of generating tubes connecting said drums, a supplemental drum located in front of said lower drum, tubes directly connecting said lower and supplemental drums, a transverse water chamber intermediate the levels of the upper and lower drums and substantially under the front upper drum, tubes connecting said supplemental drum and water chamber and constituting a water-protected roof for the furnace, and tubes connecting said chamber with the front upper drum. 80

In testimony whereof I have hereunto signed my name in the presence of two subscribing witnesses.

SUSANN E. SEWALL,
Executrix of the estate of Minott W. Sewall,
deceased.
